(57) **CLAIM**

The ornamental design for a universal holder system, as shown and described.

DESCRIPTION

FIG. 1 is an upper left front perspective view of a universal holder system, showing our new design;

FIG. 2 is an upper right front perspective view thereof;

FIG. 3 is an upper right rear perspective view thereof;

FIG. 4 is a left side elevation view thereof;

FIG. 5 is a right side elevation view thereof;

FIG. 6 is a rear elevation view thereof;

FIG. 7 is front elevation view thereof;

FIG. 8 is a top view thereof; and,

FIG. 9 is a bottom view thereof.

The portions of the universal holder system shown in broken lines form no part of the claimed design. The broken lines illustrating a cardiopulmonary bypass machine depict environment and form not part of the claimed design.
